BUTTON OR THE LIKE

Edmund D. Janes, Middlebury, Conn., assignor to
 Scovill Manufacturing Company, Waterbury,
 Conn., a corporation of Connecticut

Application December 12, 1935, Serial No. 54,050

4 Claims. (Cl. 40—20)

The present invention relates to buttons and the like which have a design, character or other ornamentation on their top, and aims to provide certain improvements therein.

Heretofore it has been impossible to feed buttons having a design or ornamentation on their top, in automatic button feed mechanisms so as to definitely locate or position the design at the button-attaching station whereby to insure attaching the button to a garment or other article with the design in desired position. To do this, of course, is highly desirable, since it will thereby be possible for the design on the buttons, which may be the manufacturer's trade mark, to be always in correct position on the garments. Such proper positioning will not only enhance the appearance of the garments, but will also enable others, in viewing the garment, to read the trade-mark on the buttons at a glance, thereby adding advertising value of benefit to the manufacturer.

In a co-pending application of Jerome G. Wolff, Serial No. 54,049, filed December 12, 1935, there are disclosed various types of buttons having a design, ornamentation or trade mark on their top adapted for use in button-feeding and attaching machines, said buttons having means thereon which bears a definite relation to the design and adapted for cooperative action with means on the button-feeding mechanism for orienting the design so that it will always have a definite position when it reaches the button-attaching station. In the various modifications shown in the Wolff application aforementioned, a preliminary setting of the body portion with respect to the cap or shell is necessary in assembling the button parts in the process of manufacture to accurately register the various means on the button with the design on the cap.

According to the present invention I do away with this preliminary registration between the shell and the body of the button and provide direct registration between the design on the shell and the body portion by providing on the shell an integral tab or lip, which, in the assembling of the shell and body portion, is bent back down over the body portion and is thereat adapted for cooperative engagement with means on the button-feeding mechanism to definitely orient the design for presentation to the button-attaching or setting station.

The invention will be better understood from the detailed description which follows, when considered in conjunction with the accompanying drawing, wherein:

Figure 1 is a top plan view of a tack button embodying my invention.

Fig. 2 is a bottom plan view of the button shown in Fig. 1.

Fig. 3 is a section taken substantially along the plane of the line 3—3 of Fig. 2.

The drawing shows my invention as applied to a conventional form of tack button, which comprises a cap or shell 10 of generally circular configuration having an inturned marginal lip 11 engaging over a complementary upturned marginal lip 12 on a flange 13 extending outwardly from a cylindrical hub 14, the bottom of which has an inturned flange 15 defining an axial opening. The parts 12 to 15 may be said to constitute the body portion of the button. Mounted within the button between the cap 10 and the flange 13 is an anvil plate 16, and disposed between said anvil plate and the inturned flange 15 is a filler element 17 having an axial opening therethrough in alignment with the opening through the flange 15 for receiving the pin of a tack or staple in the course of attaching the button to a garment or other article. The cap or shell 10 on its top is provided with an ornamental design 18, herein shown as consisting of the word or trade-mark "Scovill", the name of the assignee of this invention, disposed across the button in a straight line. Obviously the design may consist of any word, character, emblem or ornamentation, as desired. The tack button thus far described is merely by way of illustration and the invention is not limited thereto but has general application to any type of tack button or top shell button, as will presently appear.

According to my invention the cap or shell 10 is formed with an integral lip or tab 19 which bears a definite relation to the design 18 on the top of the shell, and as herein shown the tab extends along the horizontal diameter of the cap or shell and has lateral edges 20 extending parallel to said diameter. The tab 19 maintains its definite relation to the design on the top after the assembly of the cap upon the body, in the course of which assembly the tab 19 is bent back over the flange 13 of the body portion.

The tab 19 being integral with the top shell 10, provides a protrusion at the back of the flange 13, which, when the button is fed down the usual track or slideway of a button-feeding mechanism, is adapted for cooperative engagement with a pointer or other means to definitely orient the design for presentation of the button with the design in proper relation to the button-attaching or setting station. The bent back tab 19,

however, being formed of relatively thin sheet metal will not interfere with the use of the button after it has been attached to a garment or other article.

5 Although I have shown and described my invention as applied to a tack button of the top shell type, it is to be understood that the concept embodied therein is also applicable to snap fastener elements and other devices which are subject to analogous problems in assembling, hence I do not wish to be limited to the present disclosure except in so far as the same falls within the scope of the appended claims.

10 15 What I claim is:

1. A button of the top shell type, comprising a top shell and a body over which the shell is mounted, said shell having a design on the top thereof, and means on the shell bearing a definite relation to the design projecting beyond the shell 20 and extending over the body of the button.

2. A button of the top shell type, comprising a top shell and a body over which the shell is mounted, said shell having a design on the top thereof and an integral tab extending over the body of the button and bearing a definite relation to the design. 5

3. A button or the like, comprising a top and a body having a flange underlying the top, said top having a design thereon and an element integral with the top bearing a definite relation to the design overlying the flange for registering the design with a button-attaching mechanism. 10

4. A button or the like, comprising a top shell and a body over which the shell is mounted having a flange underlying the top, said top shell 15 having a design thereon and a tab integral with the top shell bearing a definite relation to the design thereon overlying the flange for registering the design with a button-attaching mechanism. 20

EDMUND D. JANES.
